Patented Apr. 5, 1834.

Thomas Stegner

8135X

The Schedule referred to in the above Patent and Drawing part of the same containing a description in the words of the said Thomas Stegner himself of his improvement in the instrument and in the application of the same for the cure of all the various kinds of Rheuma.

To all to whom these presents shall come, Be it known that I Thomas Stegner of the County of Madison in the State of Wisconsin have invented a new and usefull instrument and discovered the mode of applying the same to the cure of all the various kinds of Rheuma, and that the following is a full and exact description of the construction and operation of the said instrument and of the manner of applying the same as invented and discovered by me. The opposite head is of soft wood, half oval in its shape, this is connected by its plain surface with a piece of iron adapted in shape to the plain surface of the half oval head - on the surface of this iron opposite that for the attachment of the opposite head, there is a hook the purpose of which will be explained hereafter by which the neck of the iron on which the opposite head is placed is articulated with an elastic spring made of Brass or German steel of sufficient length to extend two thirds around the head. The width of the spring decreases from its articulating to its other extremity. This spring is covered with strong thin leather and its concave surface is padded and lined to prevent its abrading the tendons integuments. The same strips of leather with which this instrument is covered is continued across the remainder of the head, and has holes in it

near the extremity of the femur, so to the hook above mentioned, about one-third of the distance from the opposite head, to the small end of the elastic spring is attached a strap of sufficient length to pass from the superior anterior spinous process of the ilium around the exterior of posterior and inferior surface of the thigh to the same point of the ilium from which it commences. In applying this instrument the opposite head is fixed medially over the opening through which which the hernia has protruded. The shape of that portion of the spring between the head and the strap is such as to prevent its pressing on the pelvis, immediately beyond the strap it fits very easily and firmly upon the pelvis, and the remainder of the spring passes but slightly, except at its small extremity which pressing closely on the ilium immediately below the superior anterior spinous process. —

The strap is intended to preserve the instrument in the situation above described until it will relax in nineteen cases out of twenty, without the employment of the strap. — The instrument may be varied in size to suit every patient. It may be required, upon what principle it produces its effects, it is this, the peculiar shape of the opposite head draws together the fascial fibers of the external and external abdominal wings, and by its pressure effects in them inflammation which causes the fascial fibers to contract. The peculiar action of its spring preserves it in a fixed position enabling the patient to attend to his ordinary occupations while the cure is effecting.
